(57) **CLAIM**

The ornamental design for a mat for small articles, as shown and described.

DESCRIPTION

FIG. 1 is a front view of an embodiment of a mat for small articles;

FIG. 2 is a right side view of the embodiment of FIG. 1;

FIG. 3 is a top view of the embodiment of FIG. 1;

FIG. 4 is a bottom view of the embodiment of FIG. 1;

FIG. 5 is a front perspective view of the embodiment of FIG. 1;

FIG. 6 is a perspective view of the embodiment of FIG. 1 shown in an exemplary environment of use;

FIG. 7 is a perspective view of the embodiment of FIG. 1 shown in a folded state; and,

FIG. 8 is a perspective view of the embodiment of FIG. 1 shown in a folded state in an exemplary environment of use. The broken lines shown in FIG. 6 illustrate an electronic device, sunglasses, and an electric device charger that form no part of the claimed design.

The broken lines shown in FIG. 7 illustrate fold lines, i.e., lines where folds occur in the claimed design in the folded state.

The broken lines shown in FIG. 8, other than the same broken lines as shown in FIG. 7, illustrate an electronic
